UNITED STATES PATENT OFFICE

ROBERT N. PARKIN, OF PADUCAH, KENTUCKY, ASSIGNOR TO SOUTHERN TEXTILE MACHINERY COMPANY, OF PADUCAH, KENTUCKY, A CORPORATION OF KENTUCKY

SEWING MACHINE AND METHOD OF FORMING STITCHES

Application filed July 17, 1930. Serial No. 463,656.

This invention relates to improvements in sewing machines and particularly to that type of sewing machine especially adapted for uniting sections of knitted materials.

5 In its broadest aspect the invention contemplates not only a novel form of sewing machine but also a novel form of stitch and method of producing a seam composed of that particular form of stitch. More specifically, the invention has for one object the production of an interlocking stitch for uniting two pieces of material. Two threads are used in producing the stitch, each thread being passed through the materials to be united, from opposite sides thereof, and loops formed therein through which the other thread is passed before said other thread itself is projected through the materials to be joined and before the looped thread is 10 withdrawn. Successively formed stitches of this character will be held against raveling out under any conditions as distinguished from the unraveling that takes place in the ordinary piece of knitted goods.

15 Another object is to provide a machine that is especially adapted for uniting two pieces of knitted materials with this form of stitch, the machine comprising a series of moving impaling pins on which the loops of the materials to be united are placed. Two thread needles operatively associated with said impaling pins are adapted to be passed back and forth through the loops on each impaling pin in the production of the 20 stitches for uniting the two materials. By having the needle thread of both needles passing through each of the aligned loops of the materials to be joined not only is an interlocking stitch produced but the cross section of the combined threads is such as to substantially fill the loops of the materials being united so that when said materials are stretched, as for instance, a sweater being placed on one's body, there will not be present 25 the row of openings or unfilled spaces that are quite often found in seams in articles such as sweaters.

Another object of the invention is to simplify the construction of the machine and, in 30 connection with dial loopers for the uniting

of knit goods, the invention also seeks to reduce the overall space occupied by the machine. In this connection, the source of power and practically all of the operating connections for the thread needles are located within the periphery or radius of the ring of impaling pins commonly employed in dial looper machines. 55

With these and other objects in view the invention consists in certain details of construction and combinations and arrangements of parts all as will hereinafter be more fully described and the novel features thereof particularly pointed out in the appended claims. 60

In the accompanying drawings:

Figure 1 is a top plan view of a machine embodying the present improvements;

Fig. 2 is an elevational view, partly in section, of a portion of the machine; 70

Fig. 3 is a similar view but showing, in section, the mounting of the needle arm supports;

Fig. 4 is a bottom view of the bed plate of the machine, the pedestal for said plate being shown in section; 75

Fig. 5 is an enlarged detail plan view of the impaling pins;

Fig. 6 is a vertical sectional view on line 6—6 of Fig. 5; 80

Fig. 7 is a horizontal sectional view on the line 7—7 of Fig. 6;

Fig. 8 is a vertical sectional view on the line 8—8 of Fig. 6;

Fig. 9 is a similar view on the line 9—9 of Fig. 6; 85

Fig. 10 is a sectional view on line 10—10 of Fig. 8;

Fig. 11 is a detail perspective view of the cams for elevating and compressing the jacks or needle thread stops; 90

Fig. 12 is a detail perspective view of one of the thread needles and its arm;

Figs. 13 to 20, inclusive, illustrate the various positions assumed by the thread needles in a complete cycle of operation of the machine; 95

Fig. 21 is a diagrammatical illustration of the cams for imparting lateral movements to the thread needles; 100

Figs. 22 and 23 are similar views showing the cams for imparting the reciprocatory motions to the needles;

Fig. 24 is a detail view, more or less diagrammatic, illustrating the stitches produced on the present machine in connection with the loops at the edge of a piece of knitted material;

Fig. 25 is a sectional view on the line 25—
10 25 of Fig. 24;

Fig. 26 is a detail perspective view of the two thread needles;

Fig. 27 is a plan view of a circular knitting machine for use in connection with tubular
15 pieces of fabric, and

Fig. 28 is a vertical sectional view on the line 28—28 of Fig. 27.

The machine illustrated in the present instance is the type commonly known as the dial looper and while the various operating parts, particularly the needles and their operating connections, might be arranged in various ways so far as the principal features of the present invention are concerned, it is preferred that the machine be mounted on a pedestal or standard 30. Mounted at the upper end of pedestal 30 is what will be termed the bed plate 31 of the machine and, as is common in this art, this bed plate has revolvably mounted thereon the impaling pins 32. These impaling pins 32 are rigidly mounted in segmental sections 33 detachably secured, in ring like form, in an annular member 34 adapted to revolve on bed plate 31. As shown in Fig. 3, this annular member 34 has a flange portion 35 which engages in a groove 36 near the periphery of plate 31, being held in said groove by a clamping ring 37. To reduce the overall dimensions as a whole, there is bolted on the standard or pedestal 30, at a point below plate 31, a support 38 for the motor 39, which serves as a source of power for the machine. The shaft 40 of the motor 39 has an extension 41 carrying a worm 42, which meshes with worm wheel 43 mounted on a vertically disposed shaft 44. Mounted on shaft 44 is a worm 45 meshing with gear 46 on a shaft 47 mounted in a bearing member 48 on the bottom face of plate 31. This shaft 47 has, at its outer extremity, a gear 49 in mesh with a ring gear 50 on the bottom of the annular member 34 in which the impaling pins 33 are carried. As will be apparent, the impaling pins may be revolved around said plate 31 through the connections just described from motor 39, the motor being included in a circuit (not shown) adapted to be opened and closed by a switch actuated by the push buttons 51 from the upper face of bed plate 31.

Shaft 44 extends above bed plate 31 and at its upper portion has mounted thereon a gear 52 that meshes with a gear 53 on a shaft 54 mounted in bearings in brackets 55 bolted on the upper face of plate 31. This shaft

54 has mounted thereon a plurality of cam members 56, 57 and 58, 59 which, in conjunction with mechanism now to be described, impart the necessary movements to the thread carrying needles of the machine. Referring particularly to Figs. 1, 2 and 3 there are two thread needles 60, 61 that are adapted to pass through loops on the impaling pins from opposite sides of said loops. Needle 61 which passes through loops from the inner side of the ring of impaling pins to the outer side, is mounted on a needle arm 62 journaled on a shaft 63, said shaft being mounted in an upwardly extending bracket 64 that, in turn, is bolted at its lower extremity by bolts 65 to the bed plate 31. The outer needle 60 is likewise mounted on an arm 66 journaled on a shaft 67 in bracket 68, which is also secured to plate 31 by similar bolts 65. In order to raise or depress the needles 60, 61 with respect to the impaling pins, bracket 68 has an offset portion 69 at its lower portion, this offset portion 69 being of such length as to be interposed between the bed plate 31 and the lower extremity of bracket 64, as shown in Fig. 3. In other words, bracket 64 is secured to the plate 31 by the bolts 65, these bolts extending through the offset 69 of bracket 68. With this arrangement, the bottom face of the offset portion 69 can be formed with a knife edge 70 bearing on the bed plate 31, and by easing up on the screws 65 at one side of this knife edge and taking up on the other screws 65 the needles 60, 61 may be adjusted vertically toward and from the impaling pins 32. Also, as shown in dotted lines in Fig. 3, the lower portion of bracket 64 is provided with elongated slots 71 to receive the bolts 65 and with a rib 72 working in a way 73 in the offset 69 of the other bracket whereby shaft 63 and needle arm 64 may be adjusted radially of the bed plate to regulate the relative positions of needles 61, 60 longitudinally of each other.

In view of the fact that the impaling pins move continuously on the bed plate 31 it is necessary to provide means for moving needles 60, 61 laterally so that they may move in unison with the impaling pins when they are in engagement with the loops of knitted fabric on the impaling pins. As will also appear, in the production of the stitch contemplated by the present invention, it is also necessary to impart a lateral movement to the needles when they are withdrawn from the goods or materials constituting the work on the impaling pins. For these reasons, the needle arms are formed with two bearings 74 for the shaft on which they are mounted, these bearings being spaced from one another so as to receive between them a yoke like member 75 carried at the outer end of rocking levers which form part of the connections for imparting lateral movement to

- the needle arms and their needles. The lever for needle 60 is indicated at 76 and the lever for needle 61 is indicated at 77. These rocking levers 76, 77 are pivotally mounted on brackets 79 bolted to bed plate 31. Preferably said levers are pivotally mounted by means of bolts 80 extending through slots 81 in said levers whereby the leverage may be altered at will.
- 10 To impart a reciprocatory motion or rocking motion to the needle arms they each have attached thereto a connecting rod, the connecting rod for needle arm 66 being indicated at 82 and the rod for arm 62 being indicated at 83. Rod 82 is connected to one arm 84 of a bell crank lever whose other arm 85 carries cam roller 86 engaging in the cam groove in the side face of camming member 56 on shaft 54. Likewise, connecting rod 83 of needle 61 is attached to one arm 84^a of the bell crank lever whose other arm 85^a carries the cam roller 86^a, which engages in a cam groove 87^a of cam member 57 on said shaft 54. For imparting the lateral motions to the needle arms the inner ends of rocking members 76, 77 carry cam rollers 88, 89 engaging in cam grooves 90, 91 in the cam members 58, 59 on shaft 54. As will appear from Figs. 1 and 3, the throw imparted to the needle arms may be regulated by reason of the fact that their connecting rods are made sectional, the sections being attached to each other by a coupling 92 in which said rod sections are threaded whereby the length of the rod may be altered at will. Also, not only may the throw of rocking levers 76, 77 be varied by altering their leverage but said levers are adjustably mounted on the brackets 79 by means of a pin and slot connection 93 (see Fig. 3).
- 40 As shown in Figs. 2 and 3, the threads 94, 95 for the needles are supplied from spools 96 suitably supported on a stand 97 above the machine. The threads are led through suitable guides from the spools to their respective needles. In Fig. 3 needle 61 is shown in full lines in its retracted position, cam roller 86 then being in engagement with the low portion of cam slot 87^a. At this time, cam roller 89 of rocking lever 77 is in engagement with that portion of its cam slot 91 which will effect a movement of needle 61 necessary to pass the end of said needle and thread 95 between needle 60 and thread 94 for the purpose of forming a loop in said thread 94, it being understood that, also, at this time, needle 60 will have been advanced through the materials being worked on so that the end thereof is in a position where thread 95 can be passed through the loop of thread 94. The 60 various positions assumed by the needles in making these loops in the threads are shown in Figs. 13 to 20, inclusive, and will be later described in detail. After needle 61 has been actuated to form a loop in thread 94 of needle 60, said needle 61 is advanced through ma-

terials on the impaling pins 32, as indicated in dotted lines in Fig. 3. This advance of needle 61 is effected by cam roller 86^a on elevated or higher positions of cam-way 87^a. When needle 61 has been advanced to the position shown in dotted lines in Fig. 3, needle 60 will have then been removed to its retracted position, at which time needle 60 will be actuated to form a loop in thread 95 and pass thread 94 therethrough. It will be understood that needle 60 and its needle arm 66 are actuated by cam slots 87 and 90 in cams 56, 58 as needle 61 is actuated from cams 57, 59.

When one of the needles has been projected or advanced through materials on the impaling pins and a loop formed in said thread and the other thread passed through said loop, the latter thread prevents the withdrawal of the loop from the materials. However, if the machine is operating and no materials are present on the impaling pins 32 the proper stitches will not be made. In fact the machine should be stopped in the absence of work. In order to avoid this stoppage of the machine in the absence of work, there is provided a series of what might be termed stops, or what are commonly called in the art jacks, which serve as substitutes for work on the impaling pins. These jacks are shown in detail in Figs. 5 to 11, inclusive, there being a jack located between each pair of impaling pins. The jacks 98 have pin like upper extremities and at their lower extremities are formed offsets 99. The bodies of the jacks are free to move vertically in slots 100 in the peripheral face of ring member 34 and their offset portions 99 rest on a ledge 101 formed by a depending portion of the ring member 34. Slots 100 are open at the periphery of ring member 34 and a band 102 is placed around the periphery of said ring for the purpose of retaining the jacks in their slots. Spaced radially inward from the depending portion 101 of ring 34 is a cam member 103, shown in detail in Fig. 11. This cam member is located at a point where it will engage the jacks as they approach the point of operation of needles 60, 61, and the formation of the cams on this cam member or plate is such that as the jacks engage the camming surface 104 they will be elevated so that their pin like upper extremities project upwardly above the impaling pins 32. This upward movement is imparted to the jacks, as just mentioned, immediately before they reach the point where they pass the needles and after they have passed the needles they engage a second cam surface 105, on plate 103, which will depress them to their original or normal position. By the provision of these jacks the machine can continue operation even though there be no work on the impaling pins because when the needle moves as it normally would, to engage work on one of the pins, it

will pass between two elevated jacks so that when the thread thereof has a loop formed therein and the other thread passed through said loop the jacks will function just as would a piece of work on the impaling pins. This will more clearly appear from Figs. 13 to 21. In Figs. 13 to 20 the upper extremities of a portion of jacks 98 are shown at *a*, *b*, *c*, *d* and *e*, it being understood that the jacks at this point are in their elevated position. At the time the needles are in the position shown in Fig. 13 cam rollers 88, 89 are in the position indicated at *A*, in Fig. 21, and cam rollers 85, 85^a are in the positions *A'*, indicated in Figs. 22, 23. Rotation of the several cams on shaft 54 brings rollers 88, 89 to positions indicated at *B*, in Fig. 21, and rollers 85, 85^a to positions *B'*, in Figs. 22, 23. This movement of the cams effects a slight lateral movement of needle 60 so that it will move laterally in unison with the impaling pins and will effect a slight retraction of said needle from between the jacks *a*, *b*, and from the loops of material that will normally be on the impaling pin located between jacks *a* and *b*. This cam movement will also effect an advance of needle 61 and a lateral movement of said needle 61 with respect to needle 60, the advance of the needle being at a little higher rate of speed than the retraction of needle 60 so that the point of needle 61 would tend to pass between thread 94 and needle 60 to form a loop in said thread, as shown in Fig. 14. When the several cam rollers reach positions indicated at *B*, *B'*, in Figs. 21 to 23, the needles would have assumed the positions shown in Fig. 15, that is needle 60 would be still further retracted and needle 61 would have entered between jacks *c*, *d*, and projected through loops impaled on the pin 32 located between said jacks *c*, *d*. When the several cam rollers reach positions *D*, *D'*, indicated in Figs. 21 to 23, the needles would have assumed the positions shown in Fig. 16, wherein needle 60 is fully retracted and needle 61 has passed further between the jacks *c*, *d*, and the loops of material that would normally be on the impaling pin located between said jacks *c*, *d*. At this time, needle 61 will be moving slightly laterally in unison with the revolving or laterally moving impaling pins, the contour of the cam grooves in Fig. 21 being such that there is always a lateral movement of the needles when they are in work engaging position. When the several cams reach the positions indicated at *E*, *E'*, in Figs. 21 to 23, the then retracted needle 60 will have been moved laterally, as shown in Fig. 17, and is ready to advance, while needle 61 is about to be retracted. The shape of the cam slots in Fig. 21 are such that when the cam rollers reach the positions indicated at *F*, *F'* needle 60 will have been advanced and moved laterally so that its point will have passed between thread 95 and needle 61, as shown in Fig. 18. As also shown

in this figure, needle 60 is in position to be further advanced between jacks *b*, *c*, as needle 61 is completely withdrawn from between jacks *c*, *d*. This continued movement of the needles is shown in Fig. 19, the needles assuming the position shown in this figure when the cam rollers have reached the position indicated at *G*, *G'*, in Figs. 21 to 23, and, as indicated in these last mentioned figures, continued movement of the several cam rollers simply moves the needle in the direction of the arrows in Fig. 19 until they next assume the position shown in Fig. 13, at which time the cam rollers will have assumed the position indicated at *A*, *A'*, in Figs. 21 to 23. On the next following cycle of operations needle 61 will pass between jacks *d* and *e* instead of between *c* and *d*. In other words, during the formation of the stitches shown in Figs. 13 to 19 the impaling pins will have been moved one step, so to speak. Likewise, when needle 60 is advanced from the position shown in Fig. 20 it will pass between jacks *c* and *d* instead of between jacks *b* and *c*, as shown in Fig. 18. In these Figs. 13 to 20 it will be understood that the impaling pins have not been illustrated in order to avoid confusion and each time one of the needles passes between two jacks, shown in these figures it is the equivalent of having advanced through fabric or loops of knitted materials impaled on the impaling pins. In Figs. 24 and 25, there is shown more or less diagrammatically the formation of the interlocking stitching produced by the present machine. In Fig. 24 loops 106 of one piece of material are seen in elevation and in Fig. 25 loops 106 as well as the loops 107 of a second piece of material are shown in section. These views also show clearly how the loops 94^a in said thread 94 are held against withdrawal from between the loops of knitted materials by the thread 95 and how the loops 95^a in said thread 95 are likewise held against withdrawal from between the loops 106 and 107 by the thread 94.

In Figs. 27 and 28 there is shown a looper machine for use in connection with tubular knitted work. In this type of machine there is a base 150 and mounted on said base is a bearing plate 151 on which is rotatably mounted a tubular impaling pin support 152. Said impaling pin support is secured to the bearing plate 151 by a clamping or holding down ring 153. At its upper extremity the impaling pin support is adapted to receive the segmental members 154 in which are secured the impaling pins 155. As will be understood the work is adapted to be suspended from the impaling pins, the greater portion of the work extending downwardly within the tubular pin support 152. On the exterior of said support there is a ring gear 156 adapted to be driven by a worm 157 on

shaft 158, torque being applied to said shaft by means of a gear 159 mounted thereon and meshing with a similar gear 160 on a shaft 161. Said shaft 161 also has mounted thereon 5 a worm wheel 162 adapted to be driven by a worm 163 on a shaft 164 driven by a motor (not shown).

The driving connections for the impaling pin support are, of course, located at one side 10 of said support and mounted on the shaft 161 are the cams 165, 166 and 167, 168 for actuating the thread needles 179, 180. The operating connections between said thread needles 179, 180 and shaft 161 are identically the 15 same as those shown in the previously described embodiment of the invention. A detail description thereof is not deemed necessary in view of this. Suffice it to say that needles 179, 180 are carried by needle arm 20 supports 181, 182 journaled on shafts 183, 184, these shafts being mounted in brackets 185, 186. For working the needle arms for the purpose of reciprocating the needles, each arm has connected thereto an adjustable rod 25 187 and each rod is connected to one arm of a bell crank lever 188, whose other arms are provided with cam rollers 189 working in cam slots or cam grooves in cams 165, 166. For imparting the lateral movements to the 30 needles for the purpose of causing them to travel in unison with the impaling pins when engaged in loops of the work on said pins and for causing each needle to be moved laterally for the purpose of passing the thread thereof 35 through a loop in the thread of the other needle, as described in connection with the other embodiment of the invention, each needle arm is adapted to be moved longitudinally of its respective shaft by means of working levers 40 190. Each of these levers has, at one end thereof, a yoke like member 191 adapted to engage between the bearing portions of its respective needle arm and at their opposite ends said working levers 190 carry cam rollers 191 working in the cam grooves 192 of 45 cams 167, 168. Threads for the two needles are indicated at 193, 194. The operation of this type of the apparatus it is believed will be readily understood without further description.

As has been before mentioned certain features of the present invention are not necessarily limited to use in looper machines. For instance, the peculiar stitch produced on the present machine may be utilized for forming a seam in any kind of fabric material. The material does not necessarily have to be knitted and where the material is not knitted the work support, or the support for the materials, need not necessarily take the form of impaling pins such as are now in general use in looper machines.

What I claim is:

1. In a sewing machine, the combination of 53 means for supporting a piece of fabric, a pair

of thread carrying needles, means for advancing each needle through the fabric and then retracting the same, one needle being advanced while the other is retracted, and means for moving each needle laterally when retracted for passing the thread thereof through a loop in the thread of the other needle. 70

2. In a sewing machine, a continuously traveling support for pieces of fabric to be united, a thread carrying needle normally positioned at each side of the fabrics on said support, means for alternately projecting said needles through the fabrics on said support, and means for moving said needles laterally for passing the thread of each needle through a loop in the thread of the other needle when the latter is in its projected position. 75

3. In a sewing machine, a continuously moving support for fabrics to be united, a thread carrying needle normally positioned at each side of said support, means for alternately projecting said needles through the fabrics on said support, means for moving said needles laterally while in engagement with said fabrics, and means for imparting a second lateral movement to each needle when in normal position to pass the thread thereof through a loop in the thread of the other needle. 80 85

4. In a sewing machine for uniting knit fabrics, the combination of a series of impaling pins, a pair of thread carrying needles, and means for moving said needles laterally for forming loops in said threads at opposite sides of the pieces of fabric to be united and passing each of said threads through the loops formed in the other thread. 100

5. In a machine for uniting knit fabrics, the combination of a series of impaling pins adapted to be inserted in loops of the fabrics to be united, a pair of thread carrying needles adapted to be projected through the fabric loops on said pins, and means for forming a loop in the thread of each needle and passing the thread of the other needle through said loop after the first mentioned needle has been projected through the fabric loops. 105 110

6. In a machine for uniting knit fabrics, the combination of a series of impaling pins adapted to be inserted in the loops of the fabrics to be united, a thread carrying needle normally positioned at each side of the fabric loops, means for projecting and retracting said needles through the fabric loops, and means for passing the thread of each needle through a loop in the thread of the other needle after the last mentioned needle has been projected through the fabric loops. 115 120

7. In a machine for uniting knit fabrics, the combination of a series of impaling pins for loops of the fabrics to be united, a thread carrying needle normally positioned at each side of the loops on said pins, means for ad-

- vancing one needle to project it through the loops on a pin into proximity to the other needle, means for passing the thread of said other needle through a loop in the thread 5 carried by the advanced needle, and means for retracting the advanced needle and simultaneously advancing said other needle through loops in said fabric.
8. In a machine for uniting knit fabrics, 10 the combination of a series of impaling pins for the loops of the fabrics to be united, a thread needle normally positioned at each side of the loops on said pins, means for projecting one needle through loops on one pin into proximity to the second needle, means 15 for passing the thread of said second needle through a loop in the thread of the first needle, and means for projecting the second needle through the loops on a second impaling pin and retracting the previously advanced needle.
9. In a machine for uniting knit fabrics, 20 the combination of a series of impaling pins for the loops of the fabrics to be united, a thread needle normally positioned at each side of the loops on said pins, means for projecting one needle through loops on one pin into proximity to the second needle, means 25 for passing the thread of said second needle through a loop in the thread of the first needle, and means for projecting the second needle through the loops on a second impaling pin and retracting the previously advanced needle, and means for passing the thread of 30 the retracted needle through a loop in the thread of said second needle.
10. In a machine for uniting knit fabrics, 35 the combination of a series of impaling pins for the loops of the fabrics to be united, a thread needle normally positioned at each side of the loops on said pins, means for projecting one needle through loops on one pin into proximity to the second needle, means for passing the thread of said second needle 40 through a loop in the thread of the first needle, and means for projecting the second needle through the loops on a second impaling pin and retracting the previously advanced needle, and means for passing the thread of the retracted needle through a loop in the thread of said second needle.
11. In a machine for uniting knit fabrics, 45 the combination of a series of impaling pins for the loops of the fabrics to be united, a thread needle normally positioned at each side of the loops on said pins, means for projecting one needle through loops on one pin into proximity to the second needle, means for passing the thread of said second needle 50 through a loop in the thread of the first needle, and means for moving said second needle longitudinally of the first needle and projecting it through the fabric loops, and means for retracting the first needle from the fabric loops during the advance of the second needle.
12. In a machine for uniting knit fabrics, 55 the combination of a series of impaling pins for the loops of the fabrics to be united, a thread needle normally positioned at each side of the loops on said pins, means for projecting one needle through loops on one pin into proximity to the second needle, means for passing the thread of said second needle 60 through a loop in the thread of the first needle, and means for moving said second needle longitudinally of the first needle and projecting it through fabric loops on a second impaling pin, and means for retracting the first needle from the fabric loops.
13. In a machine for uniting knit fabrics, 65 means for supporting loops of said fabrics in alinement with each other, a pair of thread carrying needles, means for alternately advancing and retracting said needles to successively project them through alined loops of said fabrics, and means for passing the thread of each needle when retracted through 70 a loop in the thread of the other needle.
14. In a machine for uniting knit fabrics, 75 means for supporting loops of said fabrics in alinement, a pair of thread carrying needles, means for advancing and retracting said needles to successively project them through alined loops of said fabrics to be united, and means for moving each needle when retracted laterally of the other needle and passing the thread of the first mentioned needle through 80 a loop in the thread of said other needle.
15. In a sewing machine for uniting knit fabrics, 85 means for supporting loops of said fabrics in alinement with each other, a pair of thread carrying needles, means for advancing and retracting one needle to project it through and withdraw it from alined loops of said fabrics and for simultaneously retracting and then advancing the other needle to withdraw it from and project it through 90 alined loops of said fabrics, and means for inserting each needle when retracted between the other needle and the thread carried by said other needle while said other needle is in its advanced position whereby the thread of 95 the first mentioned needle is passed through 100 a loop formed in the thread of said other needle.
16. In a machine for uniting knit fabrics, 105 a series of constantly moving impaling pins adapted to have placed thereon loops of the fabrics to be united, a pair of thread carrying needles, means for alternately advancing and retracting said needles to project them through and withdraw them from fabric loops on said pins, means for moving said needles laterally while engaged in the fabric loops, and means for passing the thread of each needle when retracted through a loop 110 in the thread of the other needle.

17. In a machine for uniting knit fabrics, the combination of a series of constantly moving impaling pins adapted to have placed thereon loops of the fabrics to be united, a 5 pair of thread carrying needles, means for advancing and retracting each needle to project it through and withdraw it from loops on said pins, means for moving each needle laterally while engaged in the fabric loops, 10 and means for forming a loop in the thread of each needle when advanced and passing the thread of the other needle through the loop so formed.

18. In a machine for uniting knit fabrics, 15 the combination of a series of impaling pins adapted to have placed thereon the loops of fabrics united, a pair of thread carrying needles, means for advancing and retracting each needle to project it through and withdraw it from the loops on said pins, means for moving each needle laterally while engaged in the fabric loops, and means for moving each needle laterally when retracted and inserting it between the other needle and 25 the thread of said other needle when said other needle is in its advanced position whereby a loop is formed in the thread of said other needle.

19. In a sewing machine, the combination 30 of a series of impaling pins, means for moving said pins laterally, a pair of thread carrying needles, means for advancing and retracting each needle longitudinally of said pins, means for passing the thread of each 35 needle when retracted through a loop in the thread of the other needle, and stops adapted to extend through the plane in which said needles move when advanced and retracted, one of said stops being positioned between 40 each pair of impaling pins.

20. In a sewing machine, the combination 45 of a plurality of impaling pins, means for moving said pins laterally, a pair of thread carrying needles, means for advancing and retracting each needle longitudinally of said pins, means for passing the thread of each 50 needle when retracted through a loop in the thread of the other needle, a stop between each pair of impaling pins, said stops being movable in unison with said pins, and means actuating said stops for temporarily positioning them across the plane in which the needles travel when they are advanced and retracted.

55 21. In a sewing machine, the combination 60 of a series of impaling pins, means for moving said pins laterally, a pair of thread carrying needles, means for advancing and retracting each needle longitudinally of said pins along one surface of said pins, means for passing the thread of each needle when retracted through a loop in the thread of the other needle, a stop slidably positioned between each pair of pins and normally located 65 to one side of the plane traversed by said 669

dles, said stops being movable with said impaling pins, and a cam engaging said stops to project each stop beyond the plane traversed by said needles as said stop approaches said needles, and to maintain each stop in such projected position until it has passed 70 said needles.

22. In a sewing machine, the combination 75 of a supporting plate, a series of impaling pins movable on said plate, a pair of thread carrying needles, a thread arm for each needle, a support on which each arm is mounted, means for rocking said arms on their supports to advance and retract each needle longitudinally of said pins, means 80 for moving each arm laterally on its support while its needle is in engagement with work on said pins, and means for imparting an additional rocking and lateral movement of each arm to pass the thread of its needle 85 when the latter is in retracted position through a loop in the thread of the other needle.

23. In a sewing machine, the combination 90 of a supporting plate, a series of impaling pins on said plate, means for imparting a lateral movement to said pins, a pair of thread carrying needles, an arm for each needle, a pivotal support for each needle arm, means for rocking said arms on their pivotal supports to advance and retract their 95 respective needles longitudinally of said pins, means for moving said needles laterally while engaged with work on said impaling pins, means for rocking said needle arms and 100 moving said arms laterally on their pivotal supports when their respective needles are in retracted position to pass the thread of their 105 respective needles through a loop in the thread of the other needle, and means for 110 adjusting the pivotal supports of said needle arms and needles to vary the distance between the impaling pins and the plane in which said needles are advanced and retracted.

24. In a sewing machine, the combination 115 of a supporting plate, a series of impaling pins on said plate, means for imparting a lateral movement to said pins, a pair of thread carrying needles, an arm for each needle, a pivotal support for each needle arm, means for rocking said arms on their pivotal supports to advance and retract their 120 respective needles longitudinally of said pins, means for moving said needles laterally while engaged with work on said impaling pins, means for rocking said needle arms and moving said arms laterally on their pivotal supports when their respective needles are in retracted position to pass the thread of their 125 respective needles through a loop in the thread of the other needle, and means for adjusting the pivotal supports of said needle arms and needles to vary the distance between the impaling pins and the plane in 129

which said needles are advanced and retracted, and means for adjusting the pivotal support of one of said needles to move said needle toward or from the other needle.

- 5 25. In a sewing machine, the combination of a supporting plate, a series of impaling pins on said plate, means for imparting a lateral movement to said pins, a pair of thread carrying needles, an arm for each needle, a pivotal support for each needle arm, means for rocking said arms on their pivotal supports to advance and retract their respective needles longitudinally of said pins, means for moving said needles laterally while engaged with work on said impaling pins, means for rocking said needle arms and moving said arms laterally on their pivotal supports when their respective needles are in retracted position to pass the thread 75
10 of their respective needles through a loop in the thread of the other needle, means for adjusting the pivotal supports of said needle arms to alter the distance between said impaling pins and the plane traversed by 80
15 the needles when advanced and retracted, and means for adjusting one of said pivotal supports for regulating the distance between the points of the two needles.
- 20 26. In a sewing machine of the dial looper type the combination of a standard, a plate mounted on said standard, a series of impaling pins rotatable on said plate, a pair of thread carrying needles operatively associated with said impaling pins, a driven shaft, 85
25 bearings for said shaft on said plate, a plurality of cams on said driven shaft, and connections between said cams for reciprocating said needles and moving said needles laterally.
- 30 27. In a sewing machine of the dial looper type, the combination of a standard, a motor support on said standard, a plate on said standard, a series of impaling pins revolvably supported at the periphery of said plate, a cam shaft, bearings on said plate for said cam shaft, thread carrying needles operatively associated with the impaling pins, a pair of cams on said cam shaft, connections between each of said cams and one 90
35 of said needles for reciprocating the same, a second pair of cams on said cam shaft, and connections between said second pair of cams and said needles for moving the latter laterally.
- 40 28. In a sewing machine of the dial looper type, the combination of a standard, a plate on said standard, a series of impaling pins revolvably supported at the periphery of said plate, a pair of thread carrying needles operatively associated with said impaling pins, 95
45 needle arms, bearings for said needle arms mounted on said plate, a driven shaft, bearings for said driven shaft mounted on said 100
50 plate, a plurality of cams on said driven shaft, 105
55 laterally.

28. In a sewing machine of the dial looper type, the combination of a standard, a plate on said standard, a series of impaling pins revolvably supported at the periphery of said plate, a pair of thread carrying needles operatively associated with said impaling pins, needle arms, bearings for said needle arms mounted on said plate, a driven shaft, bearings for said driven shaft mounted on said 110
60 plate, a plurality of cams on said driven shaft, 115
65 laterally.

shaft, and connections between said cams and needle arms for rocking said arms and for moving said arms laterally of their bearings.
